UNITED STATES PATENT OFFICE.

OLIVER P. LE COMPTÉ, OF BALTIMORE COUNTY, AND SAM A. CAHN, OF BALTIMORE, MARYLAND, ASSIGNEES TO MILLER SAFE COMPANY, OF BALTIMORE, MARYLAND, A CORPORATION OF MARYLAND.

SAFE.

Application filed December 4, 1925. Serial No. 73,105.

An important element in the storage of valuable but bulky merchandise as furs and the more expensive textile materials in safes, is the excess of floor space which is required 5 for the operation of the present type of swinging doors. Swinging doors are also comparatively difficult to handle on account of the off-centre suspension, and centre pivoted doors obstruct the door opening.

10 Sliding doors by which both difficulties may be avoided, have not come into general use for this purpose on account of the difficulty heretofore encountered in making them burglar proof to a sufficient degree to meet 15 the requirements.

The present invention relates to a sliding door safe particularly adapted to the storage of merchandise but capable of other applications. The construction which is the subject 20 of the invention not only overcomes the difficulties incident to swinging doors as above outlined, but provides a sliding door safe in which the doors are closed, rigidly fastened together and interlocked, 25 and completely sealed to a minute degree throughout the entire length of the meeting edges, and are also supported at the other three edges by seating in grooves in the safe walls, so that no greater possibility of prying 30 the doors presented in the sliding door structure than in the present existing type of swinging doors.

The construction described and claimed has the further advantage that it obtains an 35 insurance rating higher than that which would be determined by the thickness of the doors in the ordinary type of structure, because of a feature of the improved structure, whereby the doors are reinforced as to all 40 four edges, the arrangement of the reinforce being regarded as of importance.

In the accompanying drawing we have 45 illustrated a sliding door safe structure embodying the features of our invention in what is regarded as the preferred form.

In the drawings—

Figure 1 is a front elevation of the safe closed.

Figure 2 is a similar view showing the 50 doors partly open.

Figure 3 is a section on the line 3—3, Figure 2, on a larger scale, the central portions of the structure being broken away for convenience of illustration.

Figure 4 is an inside elevation looking at 55 the meeting edges of the doors and showing them fastened.

Figure 5 is a section on the line 5—5 of 60 Figure 4 showing the meeting edges of the doors closed and locked.

Figure 6 is a horizontal section on the line 6, 6 of Figure 1 showing the lefthand front corner of the safe with the door closed.

Figure 7 is a section on the line 7—7 of 65 Figure 1 showing the righthand front corner of the safe with the righthand door closed.

Figure 8 is a section on line 8—8 Figure 5.

Referring to the drawings by numerals, 70 each of which is used to indicate the same or similar parts in the different figures, the safe structure indicated in a general way by reference character 1, is built up in any suitable manner. As shown, it is composed 75 of an outside plate 2, an intermediate layer of insulating material or filling 3 and an inside plate 4 of comparatively thin sheet metal. The inside plate 4 is protected as shown by lining 5 of wood. The corners of 80 the safe are reinforced by vertical and horizontal angle irons 6, 7, and 8 at the sides, top and bottom.

The door opening 10 as shown is surrounded by a door frame composed of angle 85 irons 11 having a narrow web 12 inserted between the walls 2, 3, 4 and the reinforcing angles 6, 7, 8, and a wider web 14 which overlies the edge portion of the side walls and the top and bottom walls adjacent the 90 opening. The door, groove or pocket 15 for the lefthand door 19 is formed between steel plates or bars 16 and 17 secured to the web 14 of the angle 11 which forms the door frame overlying the outer and inner edges 95 of the same on the flat surface presented toward the door opening and spaced apart to form the groove or pocket 15. It will be noted that in the construction shown the edge 18 of the corner angle 6 overlies and 100 covers the outer edge of the bar 16 and tends to prevent prying. The pocket or groove 20 for the righthand door 26 in the form of the invention shown is formed between the projecting lip 21 of the righthand angle 6 105 and a steel strip or bar 22 secured to and overlying the wide web 14 of the frame angle.

The top and bottom grooves 24 for the lefthand door 19 and the top and bottom grooves 25 for the righthand door 26 are continuous with the side grooves and pockets 15 and 20, respectively, the grooves 25 being formed between the edges of the top corner angle 7 and the top guide bar 27, the bottom groove or pocket 25 being formed between the bottom angle 8 and the bottom guide bar 28, the top groove 24 being formed between the top inside guide bar 29 and the top guide bar 27, and the bottom groove or pocket 24 being formed between the bottom guide bar 28 and the bottom inside guide bar 30.

The lefthand door 19 and the righthand door 26, the latter being on the outside, as seen in Figure 3, are reinforced as to all four edge portions. The lefthand door is reinforced as to each of its four edges or edge portions by angle irons 50 at the right side, 51 at the top, 52 at the bottom, 53 at the left side, one such angle iron extending along each edge having one web overlying the inner face of the plate and secured thereto, the other web projecting inwardly at right angles to the door proper. The righthand door is reinforced by angles on three sides, i. e., at the top 54 and the bottom 55, and the righthand side 56, the lefthand side or edge which overlaps the other door in closed position, having the plate 32 of which the door is formed, turned inwardly at the meeting edge in the form of a flange 33. The flange 33 is in turn reinforced by a hook plate 34 having a narrow edge flange 35 extending along its inner vertical edge and projecting backwardly to the right, i. e., in the direction of motion of the door in closing. The righthand edge of the lefthand door is provided with a similar hook plate 37 secured to the edge of the door plate and to the inwardly projecting flange 58 of the angle 50 of the lefthand door. The hook plate 37 has a narrow flange or hook 38 on its outer edge turned to the left, i. e., in the direction of the door in closing.

The hooks or flanges 35 and 38 overlap as shown in Figure 5 when the door is closed, and both flanges are preferably tapered, forming inclined surfaces, the contacting surfaces being shown in cross-section in Figure 5 at 39. This gives a wedging action forcing the doors together when closed. The overlapping portion forms an interlock which prevents prying of the doors.

The lefthand door, as shown, is further formed with a raised edge portion 40 to contact with the edge of the righthand door. This gives the effect of cutting away or hollowing out the main surface of the door and prevents rubbing of the righthand door on the painted outside surface of the lefthand door when the doors are in operation.

In the form of the invention shown the

raised surface 40 is formed by offsetting the edge of the plate and the space at the back of the plate formed by the offset is filled in any suitable manner as by a metal strip 41.

The reinforcing angles at the edges of the doors are placed in definite relation to the rest of the structure to serve the functions stated to the best advantage. The angle at the righthand edge of the lefthand door is placed as shown with the projecting leg 58 at the outer edge of the door to support the hook plate 37 and reinforce the meeting edges of the doors. The angle 53 at the lefthand edge of the lefthand door where it enters the seat or groove 15 in the door frame, is placed with its inwardly projecting leg 60 at right angles to the door spaced away from the edge of the door. The other leg 61 overlies the edge of the door at 62, presenting a double thickness at the edge of the door to enter the pocket or groove 15. The angle 56 at the righthand edge of the righthand door is similarly placed, and reinforces this door where it enters the pocket 20 in the same manner. The top angles 51 and 54 are secured to the top edges of the respective doors each with one leg 62 placed at the bottom projecting inwardly in a horizontal plane away from the top edge of the door, so that the upright leg 63 of each angle which is secured to the door reinforces the upper edges of the door so that the top edge of each door where it enters its respective pocket 24 and 25 is of a double thickness including the edge of the door plate and the edge of the leg of the angle iron. The angles 52 and 53 at the bottom of each door are similarly arranged, the inwardly projecting legs 65 being placed uppermost, the other leg 66 of each angle serving to form with the bottom edge of the door plate at 67 a double thickness of metal which enters and rides in the grooves or way 24, 25 at the bottom of the door opening.

From examination of Figure 3 it will be noted that each door is mounted on ball bearing rollers 69 carried by studs 70, seated in the door, the studs being threaded and the door plates and the respective angle irons 52 and 55 being bored and tapped. The horizontal or inwardly projecting flanges of the angle irons are slotted to admit the rollers, which run on the respective guide plates 28 and 30 at the bottom inside the respective doors.

Reference has already been made to the manner of securing the sliding doors at their overlapping edges to prevent prying of the doors when closed and locked. The tight closure referred to is effected by the interlocking of the flanges 35 and 38 of hook plates 34 and 37 and preferably extends the entire length of the doors. The doors are further secured in closed position by a man-

ually operable latch or check which may in turn be controlled by any suitable type of lock. The latch or check mechanism preferably secures the meeting edges of the doors at short intervals throughout their entire length. The device comprises a plurality of vertically sliding bars 75 above and 76 below the centre of the doors. These bars are sometimes referred to as goose-neck bars, the said bars being mounted on the inside of the outside, in this instance the righthand door 26 near the forward or lefthand edge thereof, so that when the doors are closed, the sliding bars just clear or lie just to the right in Figure 5 of the plane of the extreme righthand or forward edge of the inside or lefthand door, the said latter edge being, in the form shown, the righthand or forward surface of the hook bar or plate 37. The interlock or the latching operation is effected by a series of blocks 77 formed on or secured to the respective sliding bars or goose-neck bars 75 and 76, the same being placed at short intervals throughout the entire length of the bars. For each of these blocks 77 there is a corresponding notch 78, see Figures 8 and 5, in the flanged edge of the plate 37 on the forward or righthand edge of the inside or lefthand door, the notches 78 being slightly wider than and extending slightly to the rear of the block 77 to provide the necessary working clearance. The sliding bars 75 and 76 are secured to the back of the door by U-shaped members or straps 79 riveted or otherwise rigidly secured to the door at their ends and enclosing the bar, and permitting it to slide as aforesaid. These straps are placed as to the straps enclosing the bars 75 each with its top edge 80 level with the bottom of the corresponding slot 78, there being one of these straps for each block and therefore one strap for each notch. As to the bars 76, each strap is placed with its bottom edge level with the top of the corresponding slot, the straps serving not only as a guide and support for the respective bars, but as a positioning means for the blocks 77 in the free or releasing position of the latch; in other words, the latching or checking of the doors is accomplished by moving the bars 75 and 76 with the blocks 77 thereby, out of registration with the notches 78 in the flanged edge of the hook bar 75 whereby the blocks enter the path of the inside door in opening and hold both doors in closed position. The doors are unlatched or unchecked and released by moving the blocks 79 into contact with the respective straps 79 by which they are positioned opposite or aligned in the direction of traverse of the doors with the notches 78, so that the doors are free to open the blocks passing through the notches, these notches may be formed between any convenient projections on the door. It will be apparent from examination of Figure 5 and the other figures, that the doors being in closed position are seated at three edges in the grooves or pockets in the walls of the safe, and the two meeting edges being interlocked as therein illustrated, the doors may be thus locked by moving the blocks 77 out of registration with the notches 78 in which position they act as a positive bar to the motion of either door in the direction of opening tending to overlap the doors, the doors being fully opened in the extreme overlapping position in which they are in full registration. With the arrangement described no other motion of the doors from closed position is possible.

The doors and locking members are shown fragmentarily in Figure 8 in locked position, and in Figure 4 on a small scale in side view in locked position. The sliding bars or goose-neck bars 75, 76 may be actuated in any suitable manner as by handle 82, Figures 1 and 2, which carries a shaft or pin 80 having a rotary bearing in the door and carrying on its opposite end inside the safe a disk 83 which rotates with the handle. The disk is slotted as shown in Figure 4 at 84, the slots being as shown horizontal in the locked position of the door, but this point is hardly material. The slots are engaged by pins 85 in the ends of the sliding or goose-neck bars, the lower bar 76 being offset so that the pin carried thereby may engage the outside slot, the offset being the origin of the term goose-neck.

By rotating the handle 82, the sliding bars are moved, the lower one up and the upper one down from the position shown in Figure 4 through a short distance preferably equal to the vertical width of the slots 78 which motion of the bars is sufficient to latch or check and uncheck the doors.

The latch may be utilized as a burglar-proof locking device by so placing the combination or other lock 87 that the bolt 88 engages a notch or tooth 89 on the disk, preventing rotation of the disk to unlatched position.

The operation of the safe and the advantages of the construction described have been discussed in the preamble and description. Briefly some of the more prominent advantages consist in the interlocking of the doors at their overlapping edges in closed position throughout their entire length and the wedging action whereby the doors are forced together at the overlapping edges when closed so that there is no chance to insert a pry. The checking or latching arrangement whereby a series of blocks secured to one door are moved into and out of the path which the other door must traverse in moving it into open position, the blocks being arranged or spaced along the entire

length of the overlapping edges has great advantages in the way of security and also as arranged in the way of convenience and ease of operation.

- 5 The reinforcing of the corners of the doors of the safe with hard angle irons, one leg of each angle at the front of the safe projecting over the door opening so that it in a way interlocks with the door has great
 10 advantages in the way of protection against prying at the edges of the door, and the security thus attained is enhanced by the door frame construction of heavy angles, one leg of each angle being fastened to the
 15 corresponding corner angle, and the reinforcing of the doors at the edges by means of angles, one leg of each angle overlying the inside surface of the edge portion of the door, so that the leg of the angle as
 20 well as the edge of the door plate enters the groove or pocket in the frame gives a rigidity and security of construction corresponding to that of a structure of plate of much greater weight than that embodied
 25 in the doors. The possibility of making the doors comparatively light thus achieved gives increased ease of operation of the doors as compared to the security and rigidity of the structure and reduction of cost.
 30 We have thus described specifically and in detail a single embodiment of our invention in order that the nature and operation of the same may be clearly understood; however, the specific terms herein are used
 35 descriptively rather than in a limiting sense, the scope of the invention being defined in the claims.

What we claim and desire to secure by Letters Patent is:

- 40 1. A safe having inside and outside overlapping sliding doors, the safe walls and the doors having an interlocking connection on three edges of each door in the closed position of the latter, the fourth edges of
 45 the two respective doors being overlapped in said closed position, and each door having at the overlapping edge a portion projecting in the direction of closing, the projecting portions being interlocked inside the
 50 safe in the closed position of the doors both doors having integral outer surface portions and the outer door having a flange integral therewith, which flange covers and encloses the interlocking projections and closely contacts the inner door in the closed position of the doors.
 55

2. A safe having inside and outside overlapping sliding doors, the safe walls and the doors having an interlocking connection on three edges of each door in the closed position, the fourth edges of the two doors being overlapped in the closed position of the doors, and each door having at the overlapping edge a portion projecting in the
 60 direction of closing, the said projecting por-
 65

tions being interlocked in the closed position of the doors, the inside door having a raised portion on the outside surface of the overlapping edge portion covered by the outside door in closed position, the raised portion serving as a bearing for the outer door to prevent contact of the outer door with the main outer surface of the inside door.

3. A safe having inside and outside overlapping sliding doors, the safe walls and doors having means forming in closed position an interlocking relation between the safe walls and doors throughout three edges of each door, the doors overlapping with each other at the fourth edge, and each door having extending along the entire length of the overlapping edge a projecting portion extending backwards in the direction of closing, the said portions being overlapped inside the safe and in close contact in the said closed position.

4. A safe having outside and inside sliding doors, the safe and doors having means forming an interlocking relation between the safe walls and doors throughout three edges of each door, and the doors being in contact with each other at the fourth edge in closed position, each door having along substantially the entire length of the contacting edges portions extending backwards in the direction of closing, said portions being interlocked and in close contact in the said closed position, the interlocking portions having inclined contacting edges by which the overlapping edges of the door are forced together in closed position, producing a tight closure which is effective against prying.

5. In a safe, inside and outside sliding doors, the doors having corresponding edges in contact in closed position and having at their overlapping edges interlocking portions, the interlocking portions on each door projecting back in the direction of closing, the projecting portion on the inside door having a series of slots spaced along its length, and a sliding bar secured to the outside door to slide parallel to the overlapping edges, the sliding bar having blocks mounted thereon spaced and shaped to fit the notches in the edge of the inside door.

6. In a safe, overlapping sliding doors, the doors having corresponding edges contacting in closed position, the inside door having at its contacting edge a projecting portion with a series of slots therein spaced along its length and a sliding member mounted in the inside of the outside door to slide parallel to the overlapping edges, the sliding member having blocks mounted thereon spaced and shaped to fit the notches in the inside door.

7. In a safe, overlapping sliding doors, the doors having corresponding edges con-

- tacting in closed position, the inside door having at its contacting edge a projecting portion with a series of slots therein spaced along its length and a sliding member 5 mounted in the inside of the outside door to slide parallel to the overlapping edges, the sliding member having blocks mounted thereon spaced and shaped to fit the notches in the inside door, a series of cross-bars supporting the said sliding member in sliding relation with the inside door, the cross-bars being spaced to position the blocks opposite the notches in the edge of the outside door.
- 10 8. In a safe, inside and outside sliding doors, each door having one edge overlapped with the corresponding edge of the other door in closed position, the inside door having the overlapping edge projecting inwardly, a flanged bar overlying the edge of the door at right angles to the plane of the door having its flange spaced outwardly and projecting backward in the direction of closing, the outside door having an edge portion turned inwardly at right angles, and having a flanged bar secured to the inside of the inturned portion with its flange projecting backward in the direction of closing and in closed position of the doors 20 interlocking with the flange on the inside door.
- 15 9. In a safe, inside and outside sliding doors, one edge of each door being in contact with the other door in closed position, the inside door having a portion projecting outwardly and extending along its edge, the outside door having means mounted thereon to move in a direction parallel to the contacting edges, the outwardly projecting portion of the inside door having spaced notches along its entire length, and the moving means having blocks shaped to pass through the notches and spaced to correspond to the notches, the blocks extending inwardly beyond the projecting portion of the inside door.
- 25 10. In a safe, inside and outside sliding doors, one edge of each door being overlapped with the other door in closed position, the outside door having a sliding bar mounted thereon to slide in the direction of its length parallel to the overlapping edges, the inside door having spaced apertures along its entire length and the sliding bar having blocks shaped to pass through the apertures and spaced to correspond to the notches, the blocks extending inwardly beyond the edge of the inside door, and means for positioning the bar with the blocks opposite the notches.
- 30 11. A safe having inside and outside sliding doors, an edge of each door contacting with the corresponding edge of the other door in closed position of the doors, means mounted on the outside door to move parallel to the overlapping edges, the moving means having projections spaced in the direction of the length of the edge of the door substantially the entire length of the door, the inside door having corresponding portions projecting outwardly into the paths of said blocks over which they would move in opening the door in one position of the moving means, the projecting portions on the inside door being spaced apart to permit the blocks to pass without contacting in the other position of the sliding means.
- 35 12. A safe having a plurality of overlapping sliding doors, a door opening in which the doors are mounted, angle irons reinforcing the safe at the corners, one leg of each angle iron projecting over the door opening so that in closed position the three edges of each door are covered by the edges of the angle irons.
- 40 13. A safe having a plurality of overlapping sliding doors, a door opening in which the doors are mounted, angle irons reinforcing the safe at the corners, one leg of one angle iron projecting over the door opening so that in closed position an edge of one door is covered by the edge of the angle iron.
- 45 14. A safe having a plurality of overlapping sliding doors and a door opening grooved to admit the edges of the doors, angle irons secured to and reinforcing the edges of the doors, the angle irons at the edge portions of the doors which enter the grooves each having one leg overlying the edge of the door so that it forms a portion of the edge of the door which enters the groove, the other leg being spaced inwardly from the edge of the door and projecting backwardly into the safe.
- 50 15. A safe having overlapping sliding doors and a door opening with grooves in which the doors are mounted to slide, angles reinforcing the safe at the corners and having the edges of their legs projecting over the edges of the doors, angles reinforcing the edges of the doors and projecting into the groove in which the doors ride.
- 55 16. A safe having a door opening with grooves, a plurality of sliding doors mounted to slide in the grooves, the grooves being parallel so that the doors overlap, angle irons reinforcing the corners of the safe and projecting over the door opening so that they overlie the edges of the doors and reinforcing members secured to the edge portions of the doors on the inside and projecting into the grooves, the edges of the doors overlapping in closed position and having interlocking means.
- 60 17. A safe having a door opening, a door frame formed of angle irons having one leg parallel to the door opening and one leg parallel to the front of the safe in which the door opening is formed, angle irons

covering the corners of the safe and projecting slightly over the door opening and secured to the frame angles, bars secured to the door frame forming a plurality of door grooves therein, doors sliding in said grooves and having reinforcing members secured to their edge portions along the inside surface thereof and entering the grooves.

18. A safe having a door opening, a door frame formed of angle irons having one leg parallel to the door opening and one leg parallel to the front of the safe in which the door opening is formed, angle irons

covering the corners of the safe and projecting slightly over the door opening and 15 secured to the frame angles, bars secured to the door frame forming a plurality of door grooves therein, doors sliding in said grooves and having reinforcing angle irons secured to their edge portions along the inside 20 surface thereof and entering the grooves.

Signed by us at Baltimore, Maryland,
this 24th day of November, 1925.

OLIVER P. LE COMpte.
